UNITED STATES PATENT OFFICE

CHARLES LEHNER, OF LONG ISLAND CITY, NEW YORK, ASSIGNOR TO BIGELOW SANFORD
CARPET CO., INC., A CORPORATION OF MASSACHUSETTS

DESIGN FOR A CARPET

Application filed October 1, 1932. Serial No. 45,185. Term of patent 7 years.

To all whom it may concern:

Be it known that I, CHARLES LEHNER, a citizen of the United States, residing at Long Island City, in the county of Queens and State of New York, have invented a new, original, and ornamental Design for a Carpet, of which the following is a specification, reference being had to the accompanying drawing, forming part thereof.

The drawing illustrates a portion of a carpet showing my design.

The figure of the drawing is a face view of a piece of carpet showing my design, the repeat unit of the design being contained within the area outlined by the dot and dash lines. This unit is repeated in the relation shown by the extensions beyond the unit boundaries.

I claim:

The ornamental design for a carpet substantially as shown and described.

CHARLES LEHNER.
